[57] CLAIM

The ornamental design for a bib, as shown and described.

DESCRIPTION

FIG. 1 is a front perspective view of a bib showing my new design in the position of use;

FIG. 2 is a rear perspective view thereof;

FIG. 3 is a left side elevational view thereof, the right side being a mirror image;

FIG. 4 is a top plan view thereof;

FIG. 5 is a front elevational view thereof shown flat; and,

FIG. 6 is a right side elevational view of FIG. 5, the left side being a mirror image.

The broken lines in FIGS. 1 through 4, partially showing a human form are for illustrative purposes only and form no part of the claimed design.
